UNITED STATES PATENT OFFICE.

GEORGE D. EARLL, OF NEW YORK, N. Y.

ELECTRIC ALARM FOR PRESSURE-GAGES.

SPECIFICATION forming part of Letters Patent No. 226,165, dated April 6, 1880.

Application filed November 28, 1879.

To all whom it may concern:

Be it known that I, GEORGE D. EARLL, of the city and county and State of New York, have invented a new and Improved Electric 5 Alarm or Device for Use upon Steam-Pressure Gages, of which the following is a description, reference being had to the accompanying drawings, and to the letters of reference thereon, making a part of this specification.

10 Electric alarms have been heretofore used in connection with steam-pressure gages; but they have been so made as to be a part of the gage itself, and have required a particular or special construction of some part of the gage, 15 or they have been so constructed as to interfere more or less with the continuous and free action of the gage as a pressure-indicator.

My improved alarm device can be attached to any steam or pressure gage in use, and 20 without requiring any alteration in its parts, and does not, in any degree, interfere with the freest action of the gage as a pressure-indicator under any and all pressures. It is also 25 simple in arrangement, cheap in construction, and certain and automatic in operation.

Figure 1 shows a pressure-gage with my electric-alarm device attached. Fig. 2 is a detached view of the circuit-closing device which is attached to the gage. Fig. 3 is a sec- 30 tional view of Fig. 2 through the line $x-x$. Fig. 4 is a detached view of one end of the index-hand by which the circuit is closed.

A represents the dial of an ordinary pressure-gage, placed within a case or shell, B, and 35 upon which moves the index-hand C. To the shell or case or dial of the gage, and connected therewith by screws 1, I attach the part D, Fig. 2, which consists of a metal plate or rim, a, to which is fixed an insulated block or plate, b, most conveniently and cheaply made of hard 40 rubber, which extends over the outer edge of the dial, and to the inner side or edge of which is connected a metal face-plate, o, which is so connected therewith, as seen in Fig. 3, that it 45 will not be in contact with any part of the gage.

Connecting with the metal plate a, as shown in Fig. 2, or directly with the shell or case of the gage, is an insulated wire, 2, and another 50 similar wire, 2, passes into and through the insulated block or plate b, and connects with its

metallic face-plate o. The other ends of such wires connect with a suitable battery and alarm.

The plate o being insulated from the gage, the electric circuit between the gage and battery and the alarm is open under ordinary circumstances, and at such time or in such case no alarm is given; but whenever contact or electrical connection is made between the gage and the plate o the circuit will be closed and 55 an alarm made. This contact is effected by means of or through the common index-hand C, which indicates the pressure existing at any time when the pressure is sufficient to bring the arm or end 3 of the index-hand upon the 60 plate o, the part D being placed on the gage in such location that the end 3 of the index-hand will not come in contact with the plate o until the pressure has become such that danger may 65 be apprehended or special notice is desired.

Fig. 1 shows the index-hand in two positions, the heavy lines representing it in a position when the circuit is open and no alarm produced, and the dotted lines showing it when in contact with plate o, at which time the 70 circuit is closed and the alarm made or attention 75 called.

To insure a continued, free, and proper action of the gage as a pressure-indicator, it is necessary that the contact between the index-hand and the plate o should be effected or the 80 circuit closed in such a manner as not to interfere in any manner with the free and continuous movement of the index-hand and the natural action and operation of the gage. 85 This I accomplish by so constructing and arranging the parts that the index-hand will not strike or press against the metal plate o, and thus in any degree obstruct the free movement of the hand or affect the natural action of the 90 gage, but will slide upon or pass over such parts, and with the least possible friction or 95 resistance.

To produce the least friction between the hand 3 and the plate o as the former slides upon 95 or passes over the latter, I place upon the end of the hand a loosely-revolving wheel, 3', the hand C being also so supported on its stand- 100 ard that the periphery of the friction-wheel 3' will be only a very little below the horizontal plane of the plate o.

With such a construction and arrangement

of the parts by which the circuit is closed the gage will act as freely and perfectly as a pressure-indicator as if the alarm were not connected with it, and will continue so to act after the 5 alarm has been given, and the hand can freely pass beyond the plate if pressure is increased.

The arrangement of the plate *c*, as before described, also renders it possible to secure a continuous alarm during any desired length of 10 time or during any desired number of degrees.

My improved electric-alarm device, as will be evident from the foregoing description, can be attached to and combined with any pressure-gage without any change in its construction, and will not in any manner interfere with 15

its ready action as a pressure-indicator, and is simple in construction and automatic in operation.

What is claimed as new is—

The circuit-closing device *D*, consisting, 20 substantially, of rim *a*, insulated block *b*, and plate *c*, in combination with the index-hand and dial of a pressure-gage, the index-hand and device *D* being connected by properly-insulated wires with a suitable battery and 25 alarm, for the purposes set forth.

GEORGE D. EARLL.
